UNITED STATES PATENT OFFICE

WILLIAM L. LIGHTBOWN, OF WASHINGTON, DISTRICT OF COLUMBIA.

POLICE-NIPPERS.

SPECIFICATION forming part of Letters Patent No. 365,614, dated June 28, 1887.

Application filed May 3, 1887. Serial No. 236,992. (No model.)

To all whom it may concern:

Be it known that I, WILLIAM L. LIGHTBOWN, a citizen of the United States, residing at Washington, in the District of Columbia, have invented new and useful Improvements 5 in Police-Nippers, of which the following is a specification.

My invention relates to that class of shackles or grappling devices which are known as 10 "police-nippers," and employed for seizing a prisoner by the wrist and holding him securely until he can be taken to a place of confinement, or otherwise secured.

The object of the invention is to provide a 15 simple, convenient, and effective implement that can be quickly applied or removed without difficulty, and by means of which a prisoner can be securely held with one hand, leaving the other hand of the officer free for defense 20 or other duty, if needed.

To this end my invention consists of a police-nippers embodying the peculiarities of construction hereinafter described and claimed.

In the annexed drawings, illustrating the 25 invention, Figure 1 is a perspective view of my improved grapple or nippers, showing the jaws closed in normal position. Fig. 2 is an edge view of the handle portions of the nippers. Fig. 3 is a section through the shank portions 30 of the nipper-jaws at the point where they are pivotally connected. Fig. 4 is a side view of the nippers, showing the jaws opened, a portion of one shank being broken away to show a spring that may be placed around the pivotal 35 connection. Fig. 5 is a perspective view of the spring detached. Fig. 6 is a section through the nipper-shanks, showing the pivot and spring. Fig. 7 is a perspective detail view of a portion 40 of one jaw-shank, showing the recess for receiving one-half of the spring.

The grappling implement, as shown, comprises two corresponding parts or members, A B, of like size and form, having a pivotal connection at or near the center. Each member of the implement consists of a nipper-jaw, a, having a shank, b, and a hand-loop, c, by which the implement is grasped and manipulated. At the junction of the jaws a and shanks b the opposite members, A and B, are connected 45 by a pivot-pin, d, as shown in Figs. 1, 3, 4, and 50 6, and each member is shouldered or rabbeted in a well-known manner, as shown, to bring

the opposing jaws a a into the same plane, and yet allow their shanks and handles to pass each other freely with a swinging movement in operating the implement. The free ends of the curved or semicircular nipper-jaws a a may be made to abut directly, or they may be slightly turned outward at a', as shown, to avoid pinching 55 or bruising the flesh.

The inner face of each handle-loop c, near or at the center of its cross-bar c', is cut away on an incline, as shown in Fig. 2, to form a shoulder, e, which is adapted to interlock with a corresponding shoulder, e, on the inner face 60 of the opposite handle. These shoulders e e are preferably so located as to interlock when the handles c c are parallel, as shown in Fig. 1, and the jaws closed. As will be seen, the curved jaws a a are of such length that their 65 ends a' a' do not come quite together when the shoulders e e are in contact, and the pivoted members A and B, when closed, are thus allowed sufficient play between the opposing ends a' a' and shoulders e e to permit an adjustment of 70 the jaws a a to different sizes of wrists.

It may be remarked that the members A and B are so connected as to move freely on each other, and are capable of being sprung slightly apart to disengage the shoulders e e and permit the jaws a a to open by gravity.

In order to facilitate a ready disengagement of the interlocking shoulders e e, the ends of the handles c c are flared or turned outward at f, as shown in Fig. 2, to afford a hold for 80 the fingers in opening the implement.

If desired, a spring, g, can be provided to hold the interlocking shoulders e e in close engagement when the jaws are closed, and to force the jaws a a open, as shown in Fig. 4, 85 90 when the handles c c are sprung apart and the shoulders e e disengaged. In this form of construction each shank b will be provided on the inner side with a circular recess, h, as shown in Fig. 7, to receive one-half of the spring g, and in the center of this recess h will be a sleeve or tubular boss, k, to receive and support the pivot d, on which the members A and B turn. The spiral spring g is placed in the recesses h h around the sleeves k k, and has its opposite 95 ends bent outward, as shown in Fig. 5, and engaged in the shanks b b, as shown in Figs. 4 and 6. When the jaws a a are closed, the spring g, if employed, will tend to hold the handles 100

c c parallel to each other, with the shoulders *e e* in contact and the jaw ends *a' a'* slightly apart, as shown in Fig. 1. If it is desired, however, to adjust the jaws *a a* more closely to 5 grasp a smaller wrist, the handles *c c* can be made to slip slightly past each other under the pressure of the operator's fingers until the ends *a' a'* of the nipper-jaws come closely together. By exerting a moderate pressure with the fingers at either flaring ends of the handles *c c* they can be readily and quickly forced apart sufficiently to disengage the interlocked shoulders *e e*, when the handles can be instantly slipped by each other, assisted by the tension of the 15 spring *g*, if said spring is employed, thereby causing the jaws *a a* to open and release the wrist.

While the spring *g* is a useful attachment to the nippers, it is obvious that it is not essential, and it may therefore be dispensed with if it is desired to simplify the construction and reduce the cost of the implement.

In manipulating the nippers they can be grasped in one hand, either with the fingers on 25 the outside of the handles or in the handle-loops, as most convenient. A very firm grip can be obtained by placing the fingers on opposite sides of the shanks *b b*, and with the handles *c c* in the palm of the hand, leaving the 30 thumb free to assist in holding the device or to slip the handles past each other in releasing the jaws.

With very little practice the implement can be used successfully in one hand to take and 35 secure a prisoner, thus enabling the officer to have one hand free. It will also be observed that the construction of the nipper-jaws and their handles is so simple and uncomplicated

that the device can be readily and quickly applied or removed without inconvenience or undue violence, and without risk of injury to the hand or fingers of officer or prisoner. 40

What I claim as my invention is—

1. A police-nippers composed of two pivotally-connected members, each having a curved 45 jaw, a shank, and a handle-loop, said members being formed and connected substantially as shown, whereby the opposing jaws are brought into the same plane and the handle-loops adapted to pass each other with a swinging 50 movement in operating the jaws, substantially as described.

2. A police-nippers composed of two pivotally-connected members, each having a curved jaw, a shank, and a handle provided with a 55 shoulder to interlock with a similar shoulder on the other handle, substantially as described.

3. A police-nippers composed of two pivotally-connected members, each having a curved jaw, a shank, and a handle-loop provided with 60 a locking-shoulder and with outwardly-flared ends, substantially as described.

4. A police-nippers composed of two pivotally-connected members, each having a curved jaw, a shank, and a handle provided with a 65 locking device, said members being pivoted at the junction of each jaw with its shank, and having a spring located in said shanks and surrounding the pivotal connection, substantially as described. 70

In testimony whereof I affix my signature in presence of two witnesses.

W. L. LIGHTBOWN.
